DESCRIPTION

U.S. PATENT DOCUMENTS

FIG. 1 is a top plan view of a top part of my package/centerpiece showing my new design;

FIG. 2 is a top plan view of a bottom part of my package/centerpiece showing my new design;

FIG. 3 is a top plan view of a third part which secures the top part of my package/centerpiece in an open position;

FIG. 4 is an isometric view of my package/centerpiece, as shown in FIGS. 1 and 2, showing my new design assembled and in a closed position;

FIG. 5 is a top plan view of the design of FIG. 4;

FIG. 6 is a side elevational view of the design of FIG. 4;

FIG. 7 is an isometric view of my package/centerpiece, as shown in FIG. 4, showing my new design in the open position with the part of FIG. 3 in place;

FIG. 8 is a side elevational view of the design of FIG. 7;

FIG. 9 is an opposing side elevational view of the design of FIG. 7; and,

FIG. 10 is a top plan view of the design of FIG. 7.

The broken lines and the areas within the broken lines in the drawings represent portions of the package/centerpiece that form no part of the claimed design.
